OPTICAL INSTRUMENT

Bernard J. Wolfe, Irondequoit, N. Y., assignor to
 Bausch & Lomb Optical Company, Rochester,
 N. Y., a corporation of New York

Application September 21, 1944, Serial No. 555,104

4 Claims. (Cl. 88—33)

This invention relates to optical instruments and more particularly it has reference to desiccating devices which are used in optical instruments to absorb moisture which might otherwise impair the performance of the instrument.

One of the objects of the invention is to provide an improved means for holding the desiccating device in the instrument. Further objects are to provide a desiccating device which can be readily secured to existing types of instruments and embodies means for holding the device in spaced relation to the surface of the prism. These and other objects and advantages reside in certain novel features of construction, arrangement, and combination of parts as will hereinafter be more fully described and pointed out in the appended claims.

Referring to the drawing:

Fig. 1 is a view of a binocular body tube, with parts broken away to show the application of my invention.

Fig. 2 is a side view of my desiccating device in position on a prism support.

Fig. 3 is a top plan view of same.

Fig. 4 is a sectional view taken on line 4—4 of Fig. 3.

Fig. 5 is a sectional view taken on line 5—5 of Fig. 3.

A preferred embodiment of my invention is disclosed in the drawing wherein I have shown the invention as applied to a binocular comprising the body tube 10 within which is carried a shelf 11 for supporting the prisms 12 and 13. The prism 12 is secured to the shelf 11 by means of the posts 14 and 15 which are secured to the shelf 11. The prism 12 is located on the shelf 11 by means of a collar 16, or other suitable device, secured to the shelf 11 by screws 17. A resilient yoke 18 engages the top of prism 12 and has its ends secured, respectively, to the posts 14 and 15 by means of screws 19 and 20.

The desiccating device 21 comprises a box-like structure having a top wall 22 and an inclined side 23 which is spaced from and substantially parallel to the face 24 of the prism 12. The device 21 has a perforated wall 25 against the inner side of which is placed a sheet of filter paper 26 so as to prevent the desiccating material 27 from passing through the apertures. The device 21 is preferably formed of a molded plastic material and the desiccating material 27 may be any suitable substance, such as, silica gel.

The top wall 22 of the device 21 has on its under surface recess portions 28 and 29 which are adapted to rest, respectively, upon the screws 19

and 20 carried by the posts 14 and 15. The top wall 22 is provided with a slot 30 through which the member 18 extends. The lower side of the device 21 carries an integral depending foot 31 which is adapted to rest on the top of the shelf 11 when the device is in place in the instrument. The top wall 22 of the device 21 carries a spring member 32 which is adapted to engage the under side of cover 33 which encloses the body tube 10. It will be apparent, therefore, that when the cover 33 is in place, the desiccating device 21 is yieldably held in position by means of the spring 32. The desiccating device 21 may be readily removed by merely lifting it off of its supporting members after the cover 33 has been removed. When the device is in position, it does not contact the reflecting face of the prism and so is not apt to scratch the polished surface and thereby cause impairment of the instrument.

From the foregoing, it will be apparent that I am able to attain the objects of my invention and provide a desiccating device which may be readily applied to or removed from the instrument. The device is firmly held in position and is so constructed that it does not contact the polished face of the prism. Various modifications may obviously be made without departing from the spirit of my invention.

I claim:

1. In an optical instrument having a support, a prism mounted on the support, and means for holding said prism to the support, including a pair of spaced posts secured to the support, the combination of a desiccating device mounted in spaced relation to a surface of the prism and means for holding the desiccating device comprising recessed portions on the device which fit over the ends of said posts and a foot member on the device which rests on said support.

2. In an optical instrument, the combination of a casing, a support mounted within the casing and carrying a prism having an inclined face, means for holding the prism to the support comprising a pair of posts secured to the support on opposite sides of the prism, a desiccating device and means for holding the device in spaced relation to said inclined face, said last-named means comprising recessed portions on the device which are positioned over the ends of said posts, and a foot member projecting downwardly from the device to engage the support, a cover on the casing and spring means positioned between the cover and the device for yieldably holding the device in position.

3. In an optical instrument, the combination of a support carrying a prism having an inclined face, a desiccating device having an inclined side, and means for supporting the device with its inclined side spaced from and substantially parallel to the inclined face of the prism, said means comprising two spaced members carried by the support and a foot extending downwardly from the device, spaced portions of the device being supported by the members and the foot being carried by the support.

4. In an optical instrument having a prism with an inclined face, the combination of a casing, a support mounted within the casing and

carrying the prism, a desiccating device having a top wall and an inclined side, said device being mounted with its inclined side spaced from and substantially parallel to said face, and means for holding said device comprising three spaced supporting portions carried by the support and constructed and arranged to engage three spaced portions on the device, resilient means carried by the top wall of the device, and a cover for said casing, said resilient means being in yieldable engagement with the cover whereby the spaced portions on the device are held in yieldable engagement with the spaced portions on the support.

BERNARD J. WOLFE.
